M. McINTYRE,
LOADING APPARATUS,
APPLICATION FILED JULY 1, 1911.

1,010,291.

Patented Nov. 28, 1911.

UNITED STATES PATENT OFFICE.

MALCOLM MCINTYRE, OF NEW YORK, N. Y.

LOADING APPARATUS.

1,010,291.

Specification of Letters Patent. Patented Nov. 28, 1911.

Application filed July 1, 1911. Serial No. 636,429.

To all whom it may concern:

Be it known that I, MALCOLM MCINTYRE, a citizen of the United States of America, and residing in the borough of Manhattan, 5 in the city, county, and State of New York, have invented a certain new and useful Improvement in Loading Apparatus, of which the following is a specification.

My invention relates to loading apparatus 10 and particularly to loading apparatus designed for loading ships with coal, the special object of my invention being to provide a simple self-contained apparatus which can as a unit be readily attached to, and detached from, ships' sides.

In the accompanying drawings, Figure 1 is a side elevation of an apparatus constructed in accordance with my invention, and mounted in operative position; Fig. 2 is a 20 rear elevation of the same; and Fig. 3 is a diagram illustrating another method of mounting.

In the form illustrated the present apparatus comprises a supporting frame 5, the 25 side members of which are brought together at the upper end, to which is secured a central hook 6. The latter projects rearwardly and affords vertically adjustable means by which the frame may be suspended from the 30 rail 7 or like support at the side of a vessel 8, in proper relation to the coal port 9. An eye 10 may be provided at the top of the frame to receive a suspension rope from a derrick by which the frame is swung into 35 position on the side of the ship.

On the lower portion of the frame I have mounted hoisting devices which are preferably electrically operated. When so operated the motors 12 may be energized from 40 the generators commonly found on modern ships, by simply plugging in the conductors 13 into a receptacle 14, conveniently placed on the ship, preferably adjacent the coal port 9, as illustrated.

45 The hoisting tackle and rigging may be of any desired character. For convenience of illustration and efficiency of operation, I have illustrated a digging bucket 15, suspended on the hoisting cable 16, passing over 50 the sheave 17, at the end of the lifting split boom 18 thence over the head sheave 19 to the hoisting drum 20. The cable 21 which controls the opening and closing of the bucket 15 is secured to the usual bucket 55 wheel 22 and passes thence past the guide pulley 23 over the guide sheaves 24—25 to

the bucket operating drum 26 which is rotated in harmony with the drum 20 for the hoisting cable 16. The split boom 18 is pivoted upon the frame at 27 and is swung by the cable 28. The latter is wound on the differential drum 29 and passes over the head sheaves 30—31, on the frame, the sheave 32 at the end of the boom being engaged in a bight in the cable. This cable is 60 so arranged upon the differential drum which is operated in unison with the hoisting drum that the boom is swung in at a predetermined time and speed so as to make the bucket follow a predetermined path indicated by the dotted lines. The hopper 33 supported by brackets on the frame is constricted at its lower end, opening into a discharge chute 34 adapted to enter the port 9 in the side of the ship. A platform 35 is 70 provided for an operator who may operate the controller levers 36 by which the motors for the digging, hoisting, and opening and lowering of the bucket are controlled.

If desired the frame may be provided 80 with a bottom fork 37, as illustrated in Fig. 3, which is adapted to straddle the side rail 38 of the ship, a guy rope 39 attached to the upper eye being stretched to the ship's deck to hold the frame in position. This 85 construction is adapted for use on ships provided with deck hatches for coaling, the transfer car 40 receiving the discharge from the chute mounted on the hoisting frame. In other respects the apparatus diagrammatically illustrated in Fig. 3 is the same as 90 that shown in Figs. 1 and 2.

Various modifications of structure in which my invention is embodied will readily suggest themselves. 95

I claim as my invention:—

1. A self-contained loading apparatus readily attachable to and detachable from ships as a unit, comprising a supporting frame and means for mounting the same temporarily upon the side of a vessel, in combination with a boom, digging bucket hoisting drum, motor and hoisting tackle all carried by said frame, for the purpose described. 100

2. A self-contained loading apparatus readily attachable to and detachable from ships as a unit, comprising a supporting frame and means for mounting the same temporarily upon the side of a vessel, in combination with a boom, discharge chute, digging bucket hoisting drum, motor and 110

hoisting tackle all carried by said frame, for the purpose described.

3. A self-contained loading apparatus readily attachable to and detachable from ships as a unit, comprising a supporting frame and means for mounting the same temporarily upon the side of a vessel, in combination with boom, hoisting drum, digging bucket hoisting drum, motor and hoisting tackle all carried by said frame, for the purpose described.

4. A self-contained loading apparatus readily attachable to and detachable from ships as a unit, comprising a supporting frame and means for mounting the same temporarily upon the side of a vessel, in combination with a boom, digging bucket hoisting drum, motor and hoisting tackle all carried by said frame, together with means for controlling the position of said boom, substantially as described.

5. A self-contained loading apparatus readily attachable to and detachable from ships as a unit, comprising a supporting frame and means for mounting the same temporarily upon the side of a vessel, in combination with a boom, digging bucket

hoisting drum, motor and hoisting tackle all carried by said frame, together with a differential drum carried by said frame and operatively connected to said boom to control the position of the latter, substantially as described.

6. A self-contained loading apparatus readily attachable to and detachable from ships as a unit, comprising a supporting frame and means for mounting the same temporarily upon the side of a vessel, in combination with a boom, a drum controlling the angular position of the latter, a digging bucket, hoisting tackle therefor, a hoisting drum for operating said tackle, said hoisting and boom drums being operated in unison and all of said devices being carried by the frame, substantially as and for the purpose described.

In testimony whereof I have signed my name to this specification, in the presence of two subscribing witnesses.

MALCOLM McINTYRE.
